UNITED STATES PATENT OFFICE.

GERREIT HENDRIK VAN HENGEL, OF CINCINNATI, OHIO.

VEHICLE HEADLIGHT.

Application filed March 3, 1922. Serial No. 540,880.

To all whom it may concern:

Be it known that I, GERREIT HENDRIK VAN HENGEL, a citizen of Holland, and a resident of Cincinnati, in the county of Hamilton and State of Ohio, have invented a new and useful Improvement in a Vehicle Headlight, of which the following is a specification.

An object of my invention is to provide a vehicle headlight, adapted to preclude reflection of the rays above the horizontal.

Another object of my invention is to provide a headlight for motor vehicles, into the reflector of which light it will be impossible for drivers of approaching vehicles to look, thereby precluding temporary blinding of such approaching drivers.

These and other objects are obtained by means described herein and disclosed in the accompanying drawings, in which:

Fig. 1 is a fragmental side elevation of a motor vehicle having mounted on it a headlight embodying my invention.

Fig. 2 is an enlarged vertical longitudinal sectional view of a headlight embodying my invention.

My invention comprises a reflector housing 3 carrying a reflector 4 mounted on which is a lamp 5, a truncated conical hood 6 mounted on the housing, a truncated conical casing 11 mounted within and of a slightly smaller size than the hood 6, and a secondary reflector 7 mounted on the casing at the reduced and truncated end thereof and extending within the opening 8 formed at the truncated end of said hood.

The reflector 7 is in the nature of a mirror and serves to reflect downwardly the upwardly extending rays which have passed the focal point 10 of the rays reflected from the reflector 4. The mirror is provided with a rather elongated reflecting face 9 which lies immediately above the focal point 10. This elongated face is provided because in practice it is impossible to secure a point source of light, wherefore, there is really a series of focal points in the neighborhood of the focus 10, and to return downwardly all of the upwardly bound rays, an extended reflecting face 9 is necessary. The mirror 7 is projected to some distance within the opening 8, and thereby serves as a shield precluding on-coming drivers from looking into the reflector 4.

It is readily apparent that various modifications may be made, without departing from the spirit of the invention. For ex-

ample, the upper portion of the reflector 4 may be dispensed with and a semi-truncated cone be employed, such cone having its flat face extending substantially in the horizontal and carrying the mirror 7.

A blackened circular portion 12 is disposed upon the reflector 4 so that no rays, being parallel or nearly parallel to the ground, may be deflected thru the truncated ends of the hood and casing whereby a person looking directly into the end thereof would receive no glare.

The operation of the device is readily understood and no explanation is deemed necessary, except that attention is called to the fact that altho the lamp may be varied in its relation to the reflector 4, and the mirror 7 be inclined slightly downward from the rear to the front thereof, the focus of the rays should be disposed slightly below and substantially midway of the ends of the mirror, whereby all the rays reflected by the lower portion of the reflector 4 are reflected downwardly before the vehicle by the mirror 7.

The reflector 4 is preferably elliptical in form, which will permit development of a cross beam of light.

What I claim is:

1. In a device of the class described the combination of a housing, a hood mounted upon the housing and having a substantially conical truncated form, a primary reflector in the housing, a lamp mounted in relation to the reflector so as to produce a reflected cross beam of light, a casing mounted on the housing having substantially a truncated conical form, the casing being truncated substantially at the focal point of the light rays, and a secondary reflector mounted on the casing at the truncated end thereof and extending within the truncated end of the hood and in substantial alignment with the axis of a cross beam of light reflected from the primary reflector.

2. In a device of the class described the combination of a light source, a reflector for producing a cross beam of light, and having a non-reflecting area thereon, a truncated conical casing extending from the reflector and having the truncated portion thereof disposed substantially at the focal point of the cross beam of light, a secondary reflector carried by the casing and extending forwardly from the casing above the focal point and on a line substantially par-

allel with the light source and the focal point, the non-reflecting area being substantially of the size of the opening in the reduced end of the casing and extending substantially equidistant about the line extending through the light source and the focal point, and a truncated conical housing ex-

tending about the casing and containing the secondary reflector.

In testimony whereof, I have hereunto ¹⁰ subscribed my name this 25th day of February, 1922.

GERRIT HENDRIK VAN HENGEL.
